(57) CLAIM

The ornamental design for a housekeeping cart as shown and described.

DESCRIPTION

FIG. 1 is a front perspective view of a housekeeping cart, showing our new design;

FIG. 2 is a rear perspective view of the housekeeping cart of FIG. 1;

FIG. 3 is a right side view of the housekeeping cart of FIG. 1;

FIG. 4 is a left side view of the housekeeping cart of FIG. 1;

FIG. 5 is a bottom view of the housekeeping cart of FIG. 1; FIG. 6 is a top view of the housekeeping cart of FIG. 1; FIG. 7 is a front view of the housekeeping cart of FIG. 1; and,

FIG. 8 is a rear view of the housekeeping cart of FIG. 1. The broken lines in the figures illustrate the portions of the design that form no part of the claimed design.

1 Claim, 7 Drawing Sheets(56)
